UNITED STATES PATENT OFFICE

EDWARD LYNDON, OF WESTPORT, CONNECTICUT

BATTERY CONTAINER

Refile for abandoned application Serial No. 82,730, filed January 21, 1926. This application filed May 24, 1930. Serial No. 455,382.

My invention relates to electrical storage batteries and more particularly to the containers therefor.

The batteries with which this invention is most concerned are the so called lead batteries, i. e. batteries comprising elements made of lead oxide immersed in dilute sulphuric acid. The class of containers here considered is that comprising vessels made of acid non-resisting material, such as, for instance, wood, covered with a protective acid-resisting coating.

Storage battery containers of wood coated with a layer of acid-resisting material, as now made, have not proven to be satisfactory in practice. One of the reasons for their failure is that the protective coating does not adhere uniformly to the material to which it is applied and the slightest crack or fissure in the coating will permit the acid to attack the wood.

In the practice of my invention, I make the container of a permeable material. I prefer to use wood pulp, pressed into a form suitable for my purposes. To prevent the action of the acid on the container, I do not merely cover its walls with a protective film, as has been done heretofore, but I cause the acid-resisting substance to penetrate below the surface of the wood or other acid non-resisting material. When the acid non-resisting material is easily permeable, as in the case of wood pulp, I obtain the desired penetration by dipping this material in a bath of the protective substance, or in any other manner requiring no force. But when the material is not readily penetrable, I use pressure to force the protective substance into the acid non-resisting material, as, for instance, by means of a vacuum pump. I thereby not only obtain a more uniform coating, but I also effect a continuous and closer adherence of the protective coating to the walls of the container. It is as if the coating were imbedded in the container walls by means of innumerable, minute anchors formed by the penetrating particles of the protective substance. The penetration need not be very deep. In practice, one must be guided by commercial considerations, the cost of the protective coating increasing with the amount of the substance

used in each case, and the amount, naturally, depending on the depth of penetration. I have found the rubber compound known under the name of Vulcolac excellently well suited as a protective substance for use in connection with my invention. Vulcolac is a solution of hard rubber or ebonite in an organic solvent such as solvent naphtha. It is described in the British patent for hard rubber varnishes, No. 243,966/1925. While Vulcolac is not acid-proof when in a plastic state, it acquires all of the properties of hard rubber, i. e. resistance to the acid of a battery and to the gases developed therein during charge or discharge, after it sets and hardens.

It will be seen, therefore, that in the practice of my invention the permeable material is impregnated with pre-vulcanized rubber, whereby the invention is distinguished from containers of similar material impregnated with vulcanizable rubber and vulcanized after impregnation. Nor do I limit myself to containers for use in storage batteries since, obviously, the same process may be applied to any receptacle, no matter what its form or uses may be.

It is usual to provide battery jars with supporting bridges on which the battery plates are made to rest. In the practice of my invention, the jars of acid-resisting material being eliminated, the battery plates are introduced directly into the container. Accordingly, the supporting bridges must be placed in the container itself. I make the supporting bridges, preferably, integral with the container. When I use pressed wood pulp for the material, the container is formed complete with the supporting bridges pressed out in a single piece. As a rule, the container comprises a multiplicity of cells. The multiple container is also formed complete with partitions and bridges in a single piece of pressed wood pulp, to accord with my invention. Sometimes, especially when the cells are large, I may strengthen the container with reinforcing bands of metal or other suitable material, preferably incorporated in the wood pulp. This manner of reinforcement is so well known and understood that I have deemed it unnecessary to show it in the draw-

ing, but it should be noted that reinforcements of the container in the manner indicated or in any manner known in the art form a natural modification of my invention.

5 The protective covering is applied both on the inside and the outside of the container. This prevents any moisture from affecting the wood pulp, which is important not only because of the deterioration of the material 10 due to the effect of the moisture thereon, but because, also, any undue expansion or contraction of the material caused by hygroscopic changes is eliminated thereby. The effect of expansion or contraction due to variation 15 in temperature is negligible because the coefficients of heat expansion of wood pulp and of protective substances such as I use are both of a very low order.

20 The present application is a substitution of my application Ser. No. 82,730, which has been abandoned.

25 Referring to the drawings, Figure 1 is a vertical cross section through one form of my container. Figure 2 and Figure 3 are details thereof, also in cross section. Figure 4 is a vertical cross section of my container along the line 4—4 of Figure 1. Figure 5 is a vertical cross section through another form of my container.

30 In these drawings, 1 is the container of acid non-resisting material; 2 is an acid-resisting coating; 3 is a supporting bridge for the battery plates; 4 and 5 are, respectively, negative and positive battery plates; 6 is the usual connecting strap; and 7 is the terminal post, one being provided for each strap. Between the positive and the negative plates is the usual separator 9. In the detail Figure 3, also in Figure 2, 10 is the acid-resisting 35 coating penetrating below the surface of the acid non-resisting materials of the container. In Figure 5, in addition to the above enumerated elements, 8 is a protective strip on the inner wall of the container, shown here as an 40 integral part thereof.

45 I claim:
1. A container made of permeable acid 50 non-resisting material impregnated with pre-vulcanized rubber.
2. A container made of pressed wood pulp impregnated with prevulcanized rubber.

55 3. A container made of permeable acid non-resisting material covered with a substance comprising prevulcanized rubber and penetrating below the surface of said acid non-resisting material.

60 4. A container made of pressed wood pulp covered with a substance comprising pre-vulcanized rubber and penetrating below the surface of said wood pulp.

65 5. A container made of porous, fibrous, acid non-resisting material impregnated with prevulcanized rubber.

66 6. A container made of porous, fibrous, acid non-resisting material covered with a

substance comprising prevulcanized rubber and penetrating below the surface of said acid non-resisting material.

7. The combination with a battery container made of a porous, fibrous, acid non-resisting material, of a projection on an inner wall thereof, said container, including said projection, being covered with a substance comprising prevulcanized rubber and penetrating below the surface of said acid non-resisting material.

8. A battery container made of pressed wood pulp in a form comprising supporting bridges for the battery plates on the inner bottom wall of said container and protective strips on the inner side walls thereof, said container, including said supporting bridges and said strips, being covered with a substance comprising prevulcanized rubber penetrating below the surface of said wood pulp.

20 In testimony whereof I have affixed my signature.

EDWARD LYNDON.
